ANTIFREEZE TESTER

Anthony M. Pietramale, Wheeling, Ill., assignor to I-T-E
Imperial Corporation, Chicago, Ill., a corporation of
Delaware

Filed Dec. 30, 1968, Ser. No. 15,143

Term of patent 14 years

Int. Cl. D10—07

U.S. Cl. D52—7

FIG. 1 is a perspective view of an antifreeze tester showing my new design;

FIG. 2 is a front elevation thereof;

FIG. 3 is a rear elevation thereof;

FIG. 4 is a left side elevation thereof, the right side elevation being reversely similar thereto;

FIG. 5 is a top plan view thereof; and

FIG. 6 is a bottom plan view thereof.

The dominant features of the design are shown in full lines.

I claim:

The ornamental design for an antifreeze tester, as shown and described.
